W. H. GREENLEAF

MOTOR

Filed July 10, 1922

INVENTOR

W. T. Greenleaf

Frank Johnson
ATTORNEY

UNITED STATES PATENT OFFICE.

WILLIAM H. GREENLEAF, OF HARTFORD, CONNECTICUT.

MOTOR.

Application filed July 10, 1922. Serial No. 574,011.

To all whom it may concern:

Be it known that I, WILLIAM H. GREENLEAF, a citizen of the United States, residing at Hartford, in the county of Hartford and State of Connecticut, have invented certain new and useful Improvements in Motors, of which the following is a specification.

This invention relates to a motor. The energy for effecting the action of the motor 10 may be of any proper nature although electricity is generally utilized for the purpose. In like fashion the motor can be advantageously employed for a variety of different things, although I have found the motor especially effective as the energy for operating a time-piece.

Among the objects of the invention is the provision of a device of the class set forth which is quite simple in construction and 20 which is positive, yet automatic in action and which will cause a result at stated intervals, such, for instance as in the illustration given for operating a time-piece whether in the form of a clock or otherwise.

25 In the drawing accompanying and forming part of the present specification, I have shown in detail one of the many forms of embodiment of the invention which to enable those skilled in the art to practice the same will be set forth fully in the following description. Obviously, I am not restricted to this disclosure. I may depart therefrom in a number of respects within the scope of the invention defined by the claims following said description.

Referring to said drawing:

Figure 1 is a horizontal sectional plan view on the line 1—1 of Fig. 2 looking down.

Fig. 2 is a side elevation.

40 Fig. 3 is a top plan view.

Fig. 4 is a view somewhat similar to Fig. 1, but with the parts in different positions and with portions broken away.

Fig. 5 is a detail plan view.

45 Like characters refer to like parts throughout the several views, which are on different scales.

The motor has preferably associated therewith a source of electrical energy, and this 50 may be of any proper nature although a battery meets my conditions in a quite satisfactory manner. The motor as I have noted may be employed in many different ways. It has incorporated with it what might be 55 considered a main spring and this main spring, in the present case, is what acts

through the influence of the motor and in turn the latter may be utilized for a large number of purposes, having been found particularly useful as an adjunct in a time-piece. The various parts of the motor may be sustained in any suitable manner as by the frame denoted in a general way by 2. This frame generally consists of two plates or disks 3 and 4 which are in practice virtually in exact register and which are connected by pillars or columns 5 and 6. The disk 3 constitutes a base disk, the complement of disk 4 presenting a crown disk. Associated with the framing is a second framing such as that denoted in a general way by 7 and which may sustain, for instance, a spring which represents the auxiliary spring of the appliance and which may function for operating clock work or any other proper mechanism. The second framing 7 consists as shown of disks or plates 8 and 9 spaced apart as the other disks 3 and 4 and supporting between them a spring barrel 10 which houses within it a helical spring as found in clocks and time-pieces generally. Through the spring of the barrel 10 is extended the arbor 11 to which one end of the spring in the barrel is connected, the other end of the spring being fastened to the circumferential portion of the barrel.

The arbor 11 as shown has fastened to its upper or inner end the spur gear 12 in mesh with a pinion 13 concentric and rigid with a ratchet wheel 14. It is sustained practically centrally upon the inner face of the disk or plate 3 as shown best in Fig. 2. Between the disks or plates 3 and 4 is mounted an electromagnet comprising as shown the coils 15 and 16 connected electrically as by 95 the wire 17.

As already noted the electrical energy may be supplied in any convenient manner as by the battery 18 shown in both Figs. 1 and 3. One of the terminals of this battery 100 is connected as by the wire 19 with the magnet 15. From the other terminal of the battery a wire 20 leads and has a ground connection with one of the plates (3 or 4).

The armature for the two coils 15 and 16 is denoted by 21 and is practically of elbow form being supported pivotally, as at 22, at its elbow for oscillation. The upper or longer arm of the angular armature 21 coacts directly with both magnets 15 110 and 16 as shown for instance in Fig. 1. The outer arm or branch of the angle lever has

at its free end the widened portion 23 having extended from it the longitudinally spaced pins or studs 24 and 25, extending laterally therefrom and which coact by a 5 lost motion connection with a contactor such as that denoted in a general way by 26 and hereinafter more particularly described. The shorter arm of the L-shaped armature 21 has, as represented, pivoted on 10 it the butt or body portion of a pawl 27, the butt or body of which is denoted by 28 and is pivoted directly to the armature 21. This body 28 as shown has a rigid hook 29 around which is engaged a terminal of 15 a spring 30, the other end of the spring being connected practically similarly with a hook 31 on the body or shank 32 of the detent or dog 33, this detent 33 like the pawl 27 being co-operative with the circumferential teeth of the ratchet wheel 14 which, it will be remembered, has an operative connection with the arbor 11.

Between the contactor 26 and the body or shank 32 I interpose a practically 25 U-shaped spring 34, one branch or arm of which is bent around the upper end of the pillar 35 which extends between the plates 3 and 4 and the other branch of which is hooked into a V-shaped notch 36 at the end 30 of the lug or ear 37 which extends from the short arm 38 which projects from the shank or body of the contactor 26. Said contactor 26 as shown is mounted for swinging or oscillatory movement, being pivoted at 39 between the two plates or disks 3 and 4. The pivot 39 is practically in the form of a spindle extending between and supported jointly by the plates or disks 3 and 4 and is surrounded as shown by a coiled 40 spring 40 which exerts a constant upward pressure against the body of the contactor 26 to maintain it in operative relation. The arm 41 at the upper end of the contactor has two portions or branches 42 and 43, the 45 slot or space between them being denoted by 44.

It will be assumed that the parts are connected up as illustrated in the various views and that the disks or plates 8 and 9 with 50 the intermediate elements are not present. In this event, the action would be as follows:

In Fig. 1 the motor is shown with the armature 21 in forward or extended position and with contacts 45 and 46 in circuit closed position. This allows the energy from battery 18 to energize coils 15 and 16 thereby drawing the armature 21 toward the face of magnets 15 and 16 similar to 55 position as shown in Fig. 4. This action tensions the coil spring 30 and causes the pawl 27 to engage a fresh tooth in the ratchet 14. When armature 21 has approximately reached the limit of forward movement the pin 25 in armature extension 23

engages the inner face of branch 42 of contactor 26 causing it to move to position as shown in Fig. 4 or circuit open position. The movement of the mechanism now allows the armature 21 to be again drawn away 70 from the face of magnets 15 and 16 until the position as shown in Fig. 1 is again reached, where the operation is again repeated.

It will be noted that the U-shaped spring 75 34 causes the contactor 26 to move rapidly or snap into position when closing circuit. This is accomplished by the contactor moving forward of the center line between pivots 35 and 39. When the contactor moves to circuit open position as shown in Fig. 4, the U-shaped spring causes the contactor to remain positively in circuit open position.

The main spring of the clock mechanism is situated in the barrel 10 and one end thereof 80 has a fixed connection with the arbor 11 which as will be understood extends centrally through the barrel. To this barrel 10 is fastened the spur gear 50, in mesh with the barrel pinion 51, on the arbor 52. The 85 parts described partly are quite common in clock mechanisms of various styles and therefore require no extended description, it being understood that when the spring in the barrel 10 is wound up or tensioned, it affords, by reaction, the power necessary to 90 actuate the clock work mechanism and this clock work mechanism or something of an equivalent nature may in fact be part of a time-piece or may constitute equipment in 95 connection with any other mechanism. As a matter of fact, the spring barrel 10 and the parts associated with it between the disks or plates 8 and 9, may in some cases be altogether omitted. The main spring of 100 the appliance is the coiled spring 30 shown clearly in Figs. 1, 2 and 4, the spring within the barrel 10 constituting a secondary or auxiliary spring.

When the spring within the barrel 10 is wound up to the desired extent, a pin as 53 on the arbor 11 will strike a pin as 54 on the spur gear 50, thus preventing further winding of the auxiliary spring within the barrel 10. For the purposes of my construction, the spring within the barrel 10 is considered an auxiliary spring although it is true that in a time controlled mechanism where such a spring is present, it is generally known as the "main" spring. When the pin 53 strikes the pin or stop 54, the auxiliary spring within the barrel 10 can be wound no further. Beyond this point the coiled spring 110 30 does intermittently function in the manner I have already explained.

It is obvious that in the event, the motive power or electrical current were disconnected, the reaction of the auxiliary spring in the barrel 10 would cause the clock mechanism or such other mechanism as might 115 120 125 130

be connected, to continue to function for a period of time equal to the unwinding of the auxiliary spring.

It will be remembered that I have described the framing 2 as comprising two spaced or separated plates or disks 3 and 4. The parts between the plates, have been described somewhat in detail. I find that I can secure excellent results by having one of such plates of non-magnetic material, and this I prefer to accomplish by having the plate or disk 4 of such substance and brass answers satisfactorily my requirements. The complementary plate 3 may be of iron, steel or other substance and naturally may be magnetic.

The coils 15 and 16 of the magnet have associated with them, base and crown plates and I have found that one of these plates desirably should be of non-magnetic material. For example, the base plate of the coils might be of iron, steel or equivalent magnetic material while the crown plate would be of non-magnetic material such as brass. The plates of the two coils 15 and 16 are rigidly mounted between the plates 3 and 4.

What I claim is:

1. An appliance of the character described comprising electric circuit involving

a magnet, having an armature, a circuit controlling element operable by the armature, a terminal on the magnet having a flat face, the circuit controlling member having a portion provided with a flat face, to engage 35 said other face to close the circuit.

2. An appliance of the character described comprising an electric circuit involving a magnet having an armature, a circuit controlling element operable by the armature, and means acting constantly to impart successive opposite accelerated movements to the circuit controlling member after the movement thereof has been initiated. 45

3. An appliance of the character described comprising an electric circuit involving a magnet having an armature, a circuit controlling element operable by the armature and means acting constantly to impart successive opposite accelerated movements to the circuit controlling member after such movement has been initiated independently of said means. 50

In testimony whereof, I hereby affix my 55 signature.

WILLIAM H. GREENLEAF.
